CLAIM

I claim the ornamental design for a handheld gel nail UV curing light with silicone stamper, as shown and described.

DESCRIPTION

FIG. 1 is a top perspective view of the handheld gel nail UV curing light with silicone stamper of the present invention; FIG. 2 is a bottom perspective view of the handheld gel nail UV curing light with silicone stamper of the present invention;

FIG. 3 is a front elevational view of the handheld gel nail UV curing light with silicone stamper of the present invention;

FIG. 4 is a right hand side elevational view of the handheld gel nail UV curing light with silicone stamper of the present invention;

FIG. 5 is a rear elevational view of the handheld gel nail UV curing light with silicone stamper of the present invention; FIG. 6 is a left hand side elevational view of the handheld gel nail UV curing light with silicone stamper of the present invention;

FIG. 7 is a top view of the handheld gel nail UV curing light with silicone stamper of the present invention; and,

FIG. 8 is a bottom view of the handheld gel nail UV curing light with silicone stamper of the present invention.
